UNITED STATES PATENT OFFICE.

HERBERT E. VAN DORN, OF CHICAGO, ILLINOIS.

RAILWAY-COUPING.

1,148,555.

Specification of Letters Patent. Patented Aug. 3, 1915.

Application filed August 18, 1912. Serial No. 715,756.

To all whom it may concern:

Be it known that I, HERBERT E. VAN DORN, a citizen of the United States, and a resident of the city of Chicago, in the county of Cook and State of Illinois, have invented certain new and useful Improvements in Railway-Couplers; and I do hereby declare that the following is a full, clear, and exact description of the same, reference being had 10 to the accompanying drawings, and to the numbers of reference marked thereon, which form a part of this specification.

This invention relates to improvements in railway couplers of that class in which a rigidly secured head or bolt in one drawhead engages and interlocks with a complementary head in a complementary drawhead, and acts not only to rigidly couple the drawheads, but as well simultaneously couples 20 the air and steam lines and connections.

Elevated, interurban and street car companies, and steam roads as well, have demonstrated that the methods of coupling heretofore in use are not sufficiently reliable inasmuch as trains frequently break in two by the failure of the coupler, or because of inefficient coupling, frequently resulting in serious loss and damage; and sometimes, in very serious accidents and loss of life. This, 25 of course, frequently happens when trains are passing around curves and in many instances the unequal application of stresses on the curve has occasioned such uncoupling.

The object of this invention is to afford couplers adapted when coupled, to unite with substantially the rigidity of a slide bar, and to preclude relative movement of either coupler with reference to the other.

It is also an object of the invention to afford a construction in which accidental uncoupling is an impossibility, and in which, when once coupled, the various air and steam connections are also coupled and cannot possibly become accidentally uncoupled.

It is also an object of the invention to afford a construction adapted to couple with practically any type of coupler, in which a coupling pin is employed, should such be desired.

The invention has other objects and purposes, hereinafter more clearly set forth, and, in a preferred form, is illustrated in the drawings and hereinafter more fully described.

In the drawings: Figure 1 is a top plan

view of coupled drawheads embodying my invention. Fig. 2 is a horizontal section thereof, and showing one of the hose line connections in elevation. Fig. 3 is a horizontal section of couplers embodying my invention, showing the interlocking bolts in elevation, and in the act of coupling. Fig. 4 is a similar view, showing the locking cams released from place preparatory to uncoupling. Fig. 5 is a side elevation. Fig. 6 is an enlarged front elevation. Fig. 7 is a fragmentary horizontal section illustrating a slightly different mounting of the cam. Fig. 8 is a section on line 8—8 of Fig. 7. Fig. 9 is a fragmentary plan view illustrating the lower spring casing for the locking bolt. Fig. 10 is a fragmentary detail view of the opposite end thereof. Fig. 11 is a section on line 11—11 of Fig. 1. Fig. 12 is a section on line 12—12 of Fig. 1.

As shown in the drawings: The drawhead 1, is shaped on the face thereof, to afford two flat and parallel faces on opposite sides of the drawheads, indicated by A and B, and connected by an intermediate inclined guide face C, so that when the couplers are brought together, as shown in Fig. 1, the line of engagement of the drawheads is a broken line. Each of said drawheads 1, is cored to afford an interior chamber, which opens through the outer face of the drawhead for substantially the width thereof, and is slotted through each of the side walls of the drawhead at the faces A and B.

Rigidly engaged in each drawhead is a locking head, which lies at one side of a central line therethrough, and projects outwardly from the drawhead through the flat face A. Said locking head conforms substantially with the contour of the inner side of the chamber in said drawhead in which the same is engaged, and integrally connected therewith is a tail 2, which projects 100 inwardly substantially to the axis of the drawhead, and is provided with an aperture therethrough to receive a pin or bolt 3, whereby the same is engaged in place, and in a similar manner a pin or bolt 4, extends 105 through said drawhead, and locking head, so that said locking head is rigidly engaged in the drawhead.

Extending through said flat face A, and the slot communicating therewith in the adjacent side wall of the drawhead, is a shoulder 5, integral with the locking head and

which fits in the corresponding slot in the face B, of the complementary coupler to afford an interlock between said couplers to prevent relative vertical movement of the drawheads when coupled, as the flat and inclined faces assist in preventing relative lateral movement thereof when coupled. Each of said locking heads is shaped on its outer side from said shoulder to near the extremity to afford a concave outwardly facing locking face, which inclines inwardly from said shoulder, and affords a concave recess in the outer face to receive the locking member hereinafter described. Said locking heads are complementally shaped on their inner faces to mutually engage, and for this purpose, each locking head is slightly rounded at its outer extremity 5^a and tapered, affording a flat face 6, opposite said locking recess, and which inclines across the axis of the drawhead and toward the drawhead, thence at an angle therewith and obliquely toward the opposite sides of the drawhead, and across the axis, affording a flat face 7, then outwardly and obliquely across the axis, affording a flat face 8, then inwardly and again across the axis affording a flat face 9, and to the flat inclined face 10, of the tail of the locking head. As shown, the flat inclined faces 6, 8, and 10, are substantially parallel, and said faces are directed obliquely outward, the flat faces 7 and 9, are substantially parallel and afford nearly a right angle with the aforesaid faces, and are directed obliquely inward, thus affording a succession of zigzagged or stepped faces in the complementary locking heads adapted to mutually engage when coupled, as shown in Figs. 2 and 4.

40 A rotative cam block 11, is provided in one side of the coupler, or that opposite the locking head, to engage in the recess of the complementary locking head when projected into the drawhead. For this purpose, said rotative cam block 11, is journaled in the otherwise open side of the drawhead and extends vertically therethrough, and is provided with a peripheral flange 12, near the upper end thereof to seat around the aperture therefor to support the cam block in place. Said cam block is provided on its upper end with a pintle or gudgeon 13, on the upper end of which is rigidly engaged a lever 14, to operate the same, and, as shown, a coiled spring 15, is wound about said gudgeon and at one end engages a fixed point or shoulder 16, on the drawhead, and at the other engages said lever to hold said lever at normal position for locking engagement with the cam block and locking head. Said cam block is provided at its lower end with a downwardly extending gudgeon 17, which is diametrically slotted, as shown in Fig. 11, and wound about said gudgeon and engaged at one of its ends in said slot there-

in, is a strong spring 18, the other end of which engages a suitable shoulder or abutment 19, on the under-side of the drawhead, and acts normally to return said cam block to locking position when released. As shown, a casing or cover 20, incloses said gudgeon and spring, and is secured in place by means of a cotter pin 21, or other suitable engaging means. Said cam block is cylindric for the major portion of its surface, and is cut away between its bearings in the walls of the drawhead to afford a sector shaped recess 22, which is normally in uncoupled position and faces outwardly under the action of said springs, and, on the inner side of said cam block beyond said segment shaped recess, the wall thereof is cut away to afford an eccentricity with the axis of the block, as shown in Figs. 3 and 4.

Slidably engaged within the drawhead, is a spring pressed detent comprising a bolt 23, having a head adapted to engage in said recess in the cam block at the inner side thereof. Said bolt is cored to afford an internal recess to receive a spring 24, and is provided with a longitudinally slotted aperture at its inner end, through which extends a pin 25, which is rigidly engaged in the upper and lower walls of the drawhead. An abutment block 26, is secured on said pin in the spring recess in said bolt, as shown in Figs. 2, 3, 4, and 11, and the inner end of said spring 24, engages thereon, while the outer end thereof engages said bolt and acts to project the same outwardly against the cam block.

As shown, the head of said bolt 23, is rounded on its inner side, or that adjacent the locking head, said end of the bolt being, shaped to afford a finger, adapted to engage in the inner side of the segment recess in the cam block, when the cam block is turned to release position, as shown in Fig. 4. In this position, the bolt or detent is held in engagement with the cam block by engagement also against the locking head, and in consequence, the cam block is held from movement until the beginning of the withdrawal of the respective locking heads from uncoupled relation. A sufficient clearance is afforded between the stop 27, and the inner side of the bolt, so that when the inner end of the locking head clears the head of said bolt, the cam block rotates slightly under the action of its spring, and because of the clearance between the stop 27, and the bolt 23, such slight rotation is sufficient to release the cam block from said bolt, so that the end of the locking head may be withdrawn from the drawhead without possibility of jamming between the complementary locking head and the cam block.

In the construction illustrated in Figs. 7 and 8, the bolt 23, is wholly omitted, and the cam block 28, is provided with an upper pintle 29, and a lower pintle 30, eccentric

therewith. Said pintles are journaled respectively in the bottom of the drawhead, and in a suitable bearing block 31, set in the top of the drawhead, and the upper pintle 29, is provided with a hand lever 32, as before described. The lower pintle is inclosed within a spring casing 33, within which is a torsion spring 34, which acts to rotate said cam block, so that the longest radius of the eccentric is normally held in position in the recess in the locking head when projected into said drawhead in coupled position. Owing to the extreme eccentricity of the cam block, a comparatively shallow sector 15 shaped notch or recess is required in the shorter radius of the cam block, and into which, and oblique with the axis of the cam block, the point of the locking head strikes to rotate the cam block during coupling, 20 said springs acting to return the cam blocks into locking position when the drawheads come together.

Means are provided for coupling steam and air lines simultaneously with the coupling of the drawheads. For this purpose, 25 one or more metallic tubes or pipes (dependent upon the number of such connections required for the service) are inserted obliquely through suitable apertures in each drawhead, and the locking head therein, and substantially at a right angle with the inclined face 8, of said locking head. Said pipe is provided with an external peripheral flange 36, midway in its length, which seats against 30 a suitable shoulder in the bore therefor in the locking head, and secured on said flange and bearing against the outer side of said flange, is a pushing spring 37, the outer end of which bears against a closing plate 38, 35 through which the outer extremities of said pipe pass, and which is rigidly secured by cap screws 39, or other suitable means upon the side of the drawhead.

The hose pipes 40, for air, steam, or other 45 purposes, for each end of each car, are connected directly upon the external ends of the pipes 35, in the drawheads for said car. Said pipes 35, are slidably and yieldingly engaged in the drawheads and locking heads 50 at a right angle with the obliquely and outwardly directed faces of the locking head in said drawhead, and in the same plane with the inclined guide face C, of the drawhead, and substantially parallel with the obliquely 55 and inwardly inclined faces of said locking head, as shown in Fig. 2. Said pipes are shaped or bored at their inner ends to afford a recess for a gasket 41, which lies partly within the end of the pipe, and also projects 60 slightly beyond the end of the pipe to bring said gaskets in the pipe into compression when the drawheads are coupled. As shown also, a lip or projection 42, is provided at the inner side of each of said pipes, 65 at its extremity, which projects flush with,

or slightly beyond the gasket to bear against the end of the complementary pipe in the other drawhead, as shown in Figs. 3, 4, and 11.

As the drawheads are brought to coupled 70 relation, the inclined guide faces C, on the drawhead, as well as the construction of the locking heads, necessitates a slight lateral swing of each head with reference to the other, the inclined faces C, on the drawhead 75 guiding the drawheads in the locking heads to coupled position, such relative movement of such drawheads in coupling being oblique with the axis of the drawheads and in the plane of said guide faces, and inasmuch as 80 the pipes 35, in said drawheads and locking heads lie substantially in the plane with said guide faces, it follows that said pipes are brought into alignment, and forced together end to end, the pressure applied upon the 85 gaskets in said pipes in coupling being a direct pressure longitudinally of the pipes.

The operation is as follows: The flat bearing faces A and B, of the drawhead, afford positive abutting faces for a complementary 90 drawhead, when coupled therewith, and the inclined guide face C, on each acts to direct said drawhead obliquely and laterally to bring the locking heads into coupled relation with the drawheads in exact register 95 and wedgingly engaged together by means of said locking heads. For this purpose, the inclined face 7, of each of the locking heads, is directed outwardly and substantially parallel with the inclined guide face 100 C, of the same drawhead, and in position to engage the inwardly inclined face 9, of the locking head in the drawhead coming into coupled relation. In consequence, such lateral swing of the drawheads in coming into 105 axial alignment and under the influence of the mutual engagement of the guide faces C, acts to wedgingly force said complementary inclined faces of the locking heads into positive engagement, forcing the drawheads 110 firmly together with the shoulder or rib 5^a, of the one locking head engaged in the recess therefor in the other, thus affording a positive and rigid interlock between the drawheads, and locking heads in coupled relation, both to resist lateral flexing or vertical flexing.

With the inward projection of the locking head into the drawhead, the rounded point 5^a of each strikes into the inner side of the recess in the cam block, rotating the cam blocks, as shown in Fig. 3, to permit the end of the locking head to pass the same, whereupon the springs for said cam blocks 120 reversely rotate the same, swinging the cam faces wedgingly into engagement with the locking heads in the outer recess provided therefor, as shown in Figs. 2 or 7, rigidly engaging said locking heads in unyielding 125 coupled relation, affording practically as 130

rigid an engagement as though the drawheads and locking heads were integrally connected in coupled relation.

With the slightly oblique swing occasioned by the guide faces on the drawheads, and the engagement of the complementary faces on the locking heads, as before described; and at the moment said parts come in coupled relation, the pipes extending through said arms and locking heads are brought into alinement and forced together end to end, and because of the gaskets seated in the ends of said pipes, an air and steam-tight joint is afforded. Of course, the pushing springs 37, on said pipes, exert sufficient tension as to hold such compression, acting at all times to force said pipes inwardly and to yieldingly sustain the thrust of the complementary pipes bearing thereagainst. Inasmuch as the guide faces and inclined faces of the locking head direct said pipes into positive alinement and engagement, and inasmuch as the locking heads cooperating with the inclined guide faces C, of the drawhead, and the abutting faces A and B, thereof, act to wedgily engage the drawheads in coupled relation, preventing relative movement or slip therebetween, it follows that said pipes are subjected only to direct longitudinal pressure and not in any instance to transverse or rolling pressure upon the gaskets, in consequence wear upon the gaskets is almost wholly obviated. I have provided means, however, to limit the shock in coupling upon said gaskets to prevent injury of the same, and for this purpose, a lip or projection 42, is provided at the inner end of each of said pipes at the outer side thereof, such projection being sufficiently great to bring the same into engagement with the edge of the corresponding pipe in coupling when the gaskets are compressed beyond normal coupled compression.

Inasmuch as it sometimes may be desirable to couple drawheads of a different type, and in which a pin is employed, I have provided a slotted aperture at the outer end of each of said locking heads adapted to be projected into a drawhead to receive the coupling pin, thus enabling a drawhead embodying my invention to be coupled with many other kinds of drawheads. When so coupled the shoulder 5 lies in the same plane with the buffing face B and bears against the buffing face of such other drawhead.

In uncoupling, the levers 14 are each pulled back against the tension of their springs, reversely rotating the cam block sufficiently to permit the projection on the head of the locking bolt 23, which normally rides on the rounded end of the locking head, as shown in Fig. 3, to slide forwardly and into the sector shaped recess in said cam block between the same and the end of the

locking head, as shown in Fig. 4, draft on either drawhead now permitting said locking heads and drawheads to move obliquely and laterally of each other substantially in alinement with the inclined guide faces 6, and the complementary locking faces in said locking heads, thus separating the coupled pipes by the withdrawal along an axial line thereof, one from the other, and permitting said locking heads to be withdrawn wholly from the complementary drawheads. Should the point of the locking head strike the outer edge of the cam block in said recess, said cam block in any event is free to rotate to permit full release or clearance, inasmuch as a sufficient lateral swing of the bolt 23, is permitted in any event to enable said cam block to clear the same and to release itself when rotated to normal under the impulse of its spring.

Of course, details of construction may be varied. Any desired number of hose pipe connections may be employed and numerous details of construction may be modified to suit the requirements of the service to which the device is to be subjected. For example, in later couplers such as couplers for street cars (and probably in other uses) the bolt 23, may be dispensed with, and a larger eccentricity given to the cam block, as illustrated and described with reference to Figs. 7 and 8. It is to be understood, however, that I have shown but a preferred form of the invention, and that I do not purpose limiting the patent granted on this application otherwise than necessitated by the prior art.

I claim as my invention:

1. Complementary drawheads, a locking head rigidly secured on each and projecting outwardly therefrom; a rotative spring actuated cam block in each drawhead acting automatically to hold the locking heads in coupled relation, means retracting the cam blocks in uncoupling, and a locking bolt acting to hold the same retracted during uncoupling.

2. In a device of the class described drawheads, locking heads associated therewith, each locking head having a rounded point and a concave recess at the outer side of the point, a rotative spring pressed cam block journaled in the side of each of the drawheads opposite the locking head therein and adapted to be reversely rotated during a coupling operation by the entering drawhead, and acting to rotate under the action of its spring, into the recess near the point of the entering locking head to rigidly engage the locking head in the drawhead with said locking heads interlocked with one another, and a lever for retracting said cam block into a release position to permit uncoupling of the drawheads.

3. In a device of the class described drawheads each having a flat abutting face di-

rected at a right angle with the axis of the drawhead and an intermediate guide face therebetween inclining at an angle of approximately forty five degrees to the respective abutting faces, a locking head projecting from each drawhead, a rotative cam block in each drawhead adapted to engage behind the locking head to hold the same in coupled relation, and a spring impelled 10 slidable and pivoted bolt for holding the cam block retracted during uncoupling.

4. In a device of the class described drawheads having an outer and an inner flat abutting face directed substantially at a right angle with the axis of the drawhead, an intermediate inclined guide face connecting said abutting faces, a locking head engaged in each drawhead, cam blocks acting automatically to engage the locking heads 15 in coupled relation, and hose pipe connections in each drawhead in alinement with said guide faces and adapted thereby to couple when the drawheads are coupled.

5. A device of the class described embracing complemental drawheads, each affording an inner and an outer flat guide face directed substantially at a right angle with the axis of the drawhead, an intermediate inclined guide face connecting the 20 same at substantially an angle of forty five degrees with the axis, locking heads rigidly engaged in the drawheads and having inclined faces toward said guide faces and adapted to interlock in coupling with a complemental locking head, air and steam pipe 25 connections extending through the drawheads and locking heads in alinement with said guide faces and adapted thereby to be brought into longitudinal alinement and engagement end to end when the drawheads 30 are coupled, and automatic means for holding the locking heads in coupled relation.

6. A device of the class described embracing complemental drawheads, a locking head rigidly engaged in each and projecting outwardly therefrom, and affording an outwardly directed shoulder to interfit a complemental horizontal recess in the complemental drawhead, inclined faces on each 40 locking head directed toward the axis of the drawhead, and also at substantially forty five degrees with the axis, hose connections engaged through each drawhead and locking head and parallel said inclined faces on the locking heads and adapted to be brought into positive and coupled relation when the drawheads are coupled, a gasket on the inner end of each of said hose connections, and a projection on each hose 45 connection adapted to engage the end of the other hose connection to relieve pressure on said gasket before excessive compression, and locking means for holding the locking heads in coupled relation.

65 7. In a device of the class described a

cored out drawhead, a locking head rigidly engaged therein at one side of the axis thereof, a spring impelled cam block positioned within said drawhead at the other side of the axis thereof adapted to engage the end 70 of an entering complemental locking head of another drawhead to hold said drawheads in coupled relation, a lever for retracting said cam block, and spring impelled means acting to hold said cam blocks retracted during uncoupling of the drawheads. 75

8. In a device of the class described drawheads shaped to afford outer abutting faces and an intermediate inclined guide face, a locking head in each drawhead affording an outer shoulder to engage in a complemental horizontal recess in the complemental drawhead to resist vertical flexing of the drawheads, said locking heads rigidly engaged in the respective drawheads and affording locking faces at the inner edge thereof arranged substantially at forty five degrees with the axis. 85

9. In a device of the class described interfitting complemental drawheads, each having an inclined central guide face on the abutting end thereof, acting when the drawheads are coupled to bracingly resist lateral flexing, a removable locking head rigidly engaged in each drawhead and projecting therefrom, and a shoulder at the outer side of said locking head adapted to engage in a complemental horizontal slot in the complemental drawhead to resist the vertical flexing of the drawhead. 95

10. In a device of the class described interfitting complemental drawheads, a recessed locking head rigidly engaged in each drawhead and projecting therefrom, a shoulder at the outer side of each of said locking heads adapted to engage in a complemental horizontal slot in the complemental drawhead to resist the vertical flexing of the drawheads, means within said drawheads adapted to lock said locking head in coupled 105 relation, and acting to hold the drawheads in rigid bearing face to face, mutually engaging faces on said locking heads acting together with the cam block to rigidly and wedgingly engage the drawheads in coupled 110 relation in rigid alinement face to face and substantially as a unitary structure. 115

11. In a device of the class described complemental drawheads and locking heads rigidly engaged therein and affording respectively an inclined guide face and opposed inclined locking faces, each directed at substantially forty five degrees with the axis of the drawhead, and adapted in coupling to swing one drawhead laterally of the other to afford a relative inward and lateral movement of the locking heads, spring pressed pipes engaged in each drawhead and locking head and projecting through one of the inclined walls of the latter substantially par- 125 130

allel with the inclined guide faces and locking faces, and affording at the outer ends connections for the train line pipes, a gasket at the inner end of each, a lip at the inner end of each pipe adapted to impinge the complementary pipe in coupling to limit the compression of the gasket, and springs acting to hold said pipe connections outwardly.

12. In a device of the class described a locking head affording an outer shoulder adapted to engage in a complementary recess in the complementary drawhead, and affording at its inner edge a section of zigzagged, forty-five degree engaging faces, each locking head having a slotted aperture extending through the outer end thereof to permit coupling, each locking head having a rounded point and recessed near the outer side thereof of adjacent the point, and means adapted to engage in said recessed portion to maintain said locking heads interlocked with one another and with the shoulders thereon engaged in locking relation with the recesses provided therefor in said drawheads.

13. In a coupler of the class described drawheads a rotative eccentric cam block in one thereof having a notch or recess in one side thereof to receive the point of an entering locking head of the other drawhead to rotate said cam block in moving to coupled position, a spring on said cam block acting to reverse the rotation after the projection of the point of the locking head therepast to swing the eccentric face of the cam block into locking position against the locking head, a spring pressed detent acting to engage in the recess in the cam block and between the same and the locking head when the cam block is rotated to uncoupling posi-

tion, and a lever for actuating the cam block in uncoupling. 40

14. In a device of the class described drawheads, and detachable rigidly secured locking heads therein having flat outer and inner abutting faces, an intermediate inclined guide face connecting the same, said locking heads affording outwardly directed shoulders adapted to engage in a complementary horizontal recess in the complementary drawhead, and means wedgingly engaging the locking heads in coupled relation whereby the inclined guide faces and mutual engagement of the locking heads resist lateral flexing of the drawheads, and the shoulders of the locking head interfitting the recess in the complementary drawhead resist vertical flexing of the drawheads when coupled. 45 50 55

15. In a device of the class described drawheads and recessed locking head rigidly engaged therewithin, said drawheads and locking heads acting in coupling to interfit to preclude lateral flexing and vertical flexing when coupled, a spring impelled vertically rotatable recessed cam wedgingly and rigidly engaging in the recess in the locking head to couple the same in the drawhead, a pin secured within the drawhead, and a spring impelled slidable bolt slotted to engage said pin and acting to hold said cam retracted. 60 65 70

In testimony whereof I have hereunto subscribed my name in the presence of two subscribing witnesses.
